US0D1031931S

(12) **United States Design Patent** (10) **Patent No.:** **US D1,031,931 S**
(45) **Date of Patent:** **** Jun. 18, 2024**

(54) **COMBINED HUB AND SPOUT**

(71) Applicant: **FB Global Plumbing Group LLC**,
North Olmsted, OH (US)

(72) Inventor: **Ryan Jacob Burbank**, Westlake, OH
(US)

(73) Assignee: **Fortune Brands Water Innovations
LLC**, North Olmsted, OH (US)

(**) Term: **15 Years**

(21) Appl. No.: **29/824,322**

(22) Filed: **Jan. 24, 2022**

(51) LOC (14) Cl. **23-01**

(52) U.S. Cl.

USPC **D23/238**

(58) **Field of Classification Search**

USPC D23/238-244, 252, 254-255, 257, 499;

D7/398

CPC F16K 31/602; F16K 31/605; F16K 31/607;

E03C 1/0412

(57) **CLAIM**

The ornamental design for a combined hub and spout, as shown and described.

DESCRIPTION

FIG. 1 is a perspective view of a combined hub and spout of the new design;

FIG. 2 is a front elevational view thereof;

FIG. 3 is a rear elevational view thereof;

FIG. 4 is a left side elevational view thereof, the right side elevational view being a mirror image thereof;

FIG. 5 is a top plan view thereof; and,

FIG. 6 is a bottom plan view thereof.

The broken lines are included for the purpose of illustrating portions of the article and form no part of the claimed design.

1 Claim, 4 Drawing Sheets
